UNITED STATES PATENT OFFICE.

IRWIN DUNBAR AND FRANK NORRIS, OF KIRKSVILLE, MISSOURI.

DESIGN FOR A TOY.

54,902.

Specification for Design. Patented Apr. 20, 1920.

Application filed October 25, 1919. Serial No. 333,409. Term of patent 14 years.

To all whom it may concern:

Be it known that we, IRWIN DUNBAR and FRANK NORRIS, citizens of the United States, residing at Kirksville, in the county of Adair and State of Missouri, have invented a new, original, and ornamental Design for a Toy, of which the following is a specification, reference being had to the accompanying drawing, forming part thereof.

The figure is a perspective view of a toy, showing our new design.

We claim:

The ornamental design for a toy, as shown.

IRWIN DUNBAR.
FRANK NORRIS.
